COMBINED MUSIC STAND AND AMPLIFIER HOUSING OR SIMILAR ARTICLE

Stanley Cutler, Van Nuys, and Clyde L. Tichenor, Sepulveda, Calif., assignors to Warwick Electronics Inc., Chicago, Ill., a corporation of Delaware

Filed Dec. 28, 1967, Ser. No. 9,967

Term of patent 14 years

(Cl. D56—4)

FIGURE 1 is a side, top and rear perspective view of a combined music stand and amplifier housing or similar article, showing our new design with the light shield and music rest in folded position for transport;

FIGURE 2 is a side, top and rear perspective view with the light shield and music rest raised in operative position;

FIGURE 3 is a front, top and side perspective view;

FIGURE 4 is a front elevational view;

FIGURE 5 is an opposite side elevational view; and

FIGURE 6 is a rear elevational view thereof.

The dominant features of our new design are shown in solid lines in the drawing.

We claim:

The ornamental design for a combined music stand and amplifier housing or similar article, as shown and described.
